(57) **CLAIM**

The ornamental design for a scanner handle as shown and described.

DESCRIPTION

FIG. 1 is a perspective view of a scanner handle showing our new design from the front, top, left;

FIG. 2 is another perspective view thereof showing our new design from the rear, top, left;

FIG. 3 is a left side elevation view thereof, the right side being a mirror image thereof;

FIG. 4 is a front elevation view thereof;

FIG. 5 is a rear elevation view thereof;

FIG. 6 is a top plan view thereof; and,

FIG. 7 is a bottom plan view thereof.

The broken lines illustrate portions of the scanner handle that form no part of the claimed design.

1 Claim, 7 Drawing Sheets
